(57) **CLAIM**

The ornamental design for a vacuum sweeper handle, as shown and described.

DESCRIPTION

FIG. 1 is a perspective view of a vacuum sweeper handle showing my new design;

FIG. 2 is an enlarged perspective view thereof;

FIG. 3 is an enlarged front elevation view thereof;

FIG. 4 is an enlarged top plan view thereof;

FIG. 5 is an enlarged bottom plan view thereof;

FIG. 6 is an enlarged rear elevation view thereof; and,

FIG. 7 is an enlarged side elevation view thereof, the opposite side being a mirror image.

The details shown in broken lines form no part of the claimed design.
